Primary Examiner — Angela J Lee

(57) **CLAIM**

The ornamental design for a computing device with computer generated icon, as shown and described.

DESCRIPTION

FIG. 1 is a front view of a computing device with computer generated icon; and,

FIG. 2 is an enlarged view of FIG. 1.

The broken lines showing a portion of the display screen of a computing device and unclaimed text, icons and indicia form no part of the claimed design.

1 Claim, 2 Drawing Sheets

FIG. 1

FIG. 2
